UNITED STATES PATENT OFFICE.

HENRY M. SVEBILIUS, OF CHICAGO, ILLINOIS, ASSIGNOR TO JOSEPH SALTZMAN, OF CHICAGO, ILLINOIS.

GARMENT-PRESSER.

1,070,203.

Specification of Letters Patent. Patented Aug. 12, 1913.

Application filed January 11, 1913. Serial No. 741,483.

To all whom it may concern:

Be it known that I, HENRY M. SVEBILIUS, a citizen of the United States, residing at Chicago, in the county of Cook and State of Illinois, have invented new and useful Improvements in Garment-Pressers, of which the following is a specification.

My invention relates to pressing machines employed more especially by tailors and clothing manufacturers for pressing garments, and my primary objects are to provide a manually-operated machine for the purpose above stated, which shall be of strong and durable construction, by which 10 the iron shall be caused to exert relatively great pressure with comparatively little effort on the part of the operator, and generally to so improve upon machines of this character as to cause them to better perform 20 the work for which they are intended.

Referring to the accompanying drawings—Figure 1 is a view in side sectional elevation of a machine constructed in accordance with my invention, the section being taken at the line 1 on Fig. 5 and viewed in the direction of the arrow, this view showing the machine in inoperating position. Fig. 2 is a broken section taken at the line 2 on Fig. 1 and viewed in the direction 25 of the arrow. Fig. 3 is a view similar to Fig. 1, excepting that the upper portion of the machine is shown in full elevation, this view showing the positions assumed by the parts of the machine during the pressing operation. Fig. 4 is a broken view in side elevation of one of the similar spring devices employed in connection with the iron-lowering means, for returning the parts of the machine to normal position illustrated in 30 Fig. 1. Fig. 5 is a view in rear elevation of the machine illustrated in the preceding figures; and Fig. 6, a plan view of the machine.

The frame of the machine is formed of a 45 table 7, supported on spaced uprights 8, suitably braced together to provide a rigid structure, the bed 7 being provided with leaves 9 hinged thereto, as indicated at 10, these leaves forming, when raised to the 50 position illustrated in Figs. 5 and 6, exten-

sions to the bed 7 for supporting a garment being pressed. Mounted on the forward edge of the bed 7 is a pressing-table, or buck, 11, which, in accordance with common practice, is preferably made hollow and 55 is equipped with means for heating it, as for example, the burner 12.

Coöperating with the buck 11 is a presser-head 13, pivotally connected, as indicated at 14, with the forward end of a rod 15 reciprocably supported on rollers 16 and 17 carried by a head 18, pivotally mounted, as hereinafter described, on the upper end of a 60 vertically movable shaft 19.

The presser-head 13 is adapted to be 65 raised and lowered for moving it into and out of operating position relative to the buck 11 by raising and lowering the shaft 19, and to this end, I provide the mechanism of which the following is a description: Rigidly secured to the shaft 19 is a collar 20, provided with a shaft 21, located in the rear of the shaft 19, and extending beyond the opposite sides of said collar. Pivoted at their angle portions 22 to the ends of a shaft 23, fixed in the frame of the machine, are bell-crank levers 24, spaced apart and journaled at their rear ends on the protruding ends of the shaft 21, and at their lower ends on the ends of a shaft 25, passing 70 through the angle portion 26 of a bell-crank lever 27. The lower end of the bell-crank lever 27 is bifurcated, as represented at 28, at which portion it is equipped with a shaft 29 on which is journaled the upper end of a 75 link 30, which extends between the arms 28 and is pivotally connected at its lower end through the medium of a shaft 31, with a collar 32, fixed on the lower end of the shaft 19. The upper end of the bell-crank 80 27 is pivotally connected, as indicated at 33, with the upper bifurcated end 34 of an arc-shaped link 35, the lower end of which latter is bifurcated, as represented at 36, at which it 85 is pivotally connected, as indicated at 37, with a treadle 38, pivoted, as indicated at 39, at its rear end, to the frame of the machine, the link 35 carrying a pin 40, which extends beyond opposite sides thereof and to which the forward ends of coiled springs 41, ad- 90 95 100

justably fastened at their rear ends to the frame of the machine by the fastening means 42, are secured.

It is desirable in machines of this type 5 that the presser-head 13 be capable of swinging through an arc in a horizontal plane, and that said head be adjustable up and down in order that garments of different thicknesses may be properly pressed and the degree of pressure exerted by the presser-head 10 be regulated, as conditions require. To this end, I pivotally mount the head 18 on the upper end of the shaft 19 and provide adjusting means for adjusting the head 18 on 15 said shaft, a description of these means being as follows: The shaft 19 toward its upper end is threaded, as represented at 43, and screwing thereon is a split clamping-nut 44, the head 18 being formed with spaced 20 upper and lower bearings 45 and 46, at which the head 18 is journaled on the upper end of the shaft 19 and between which the nut 44 is positioned. It will thus be understood that by turning the nut 44 in one direction or the other, the head 18, and consequently the head 13, will be raised or lowered on the shaft 19, depending upon the direction in which the nut 44 is turned, the provision of a clamping-nut preventing the 25 head 18, when swung upon the shaft 19, during the pressing operation, from affecting the adjustment of said nut.

The normal position of the machine is illustrated in Fig. 1, wherein the presser-head 13 is held in raised position by the action of the springs 41. To operate the machine for depressing the presser-head 13 against a garment on the buck, the operator bears down on the treadle 38 with the result 10 of drawing down on the link 35, which swings the bell-cranks 24 to the right in Fig. 1 and the bell-crank 27 to the left in said figure, the connections between these bell-cranks and the collars 20 and 32 on the shaft 19 causing said shaft and the parts carried thereby, as hereinbefore described, to be forced down with great pressure against the resistance of the springs 41. When it is desired that the presser-head 13 be raised for 15 interrupting the pressing operation, the operator will discontinue downward pressure on the treadle 38, whereupon, under the action of the springs 41, the connections between the treadle and the shaft 19 will be moved to the position illustrated in Fig. 1, and be held in such position until the treadle 38 is again depressed.

In order to properly guide the shaft 19 for insuring straight-line movement thereof, 20 I form in the lower end thereof a slot 47, the lower end of which is slightly forwardly offset, as represented in Figs. 1 and 3, the slotted end of this shaft extending into a recess 48 in the treadle 38 and engaging at

its slot with a pin 49, carried by the treadle. 65 It will be manifest that as the treadle 38 moves downwardly, when operated as hereinbefore described, the pin 49 will engage the rear wall of the forwardly offset portion of the slot and tend to tip the head 18 downwardly to the right in Fig. 1, and thus overcome any tendency of the iron to be tilted backwardly by reason of the change in the angular position of the bell-cranks 24 and the inherent spring in the overhanging portion 70 of the head 18, under the pressure exerted by the treadle. 75

It will be readily understood from the foregoing that by my improved connections between the treadle 38 and the shaft 19, 85 great pressure may be exerted on the shaft 19 for depressing it, with slight exertion on the part of the operator in depressing the treadle 38, and that by mounting the head 18 on the shaft 19, in accordance with my 85 present invention, a strong and durable adjustable connection is provided between said head and shaft.

What I claim as new and desire to secure by Letters Patent is: 90

1. In a machine of the character described, the combination of a stationary frame carrying a pressing-table, a movable frame, a presser-head carried by said movable frame for coöperation with said pressing-table, a bell-crank pivotally connecting said frames together, a second bell-crank pivoted to said first-named bell-crank, a link pivotally connecting said second-named bell-crank with said movable member, a treadle pivoted on 100 said stationary frame, means connected with said treadle and with said bell-crank mechanism for actuating the latter to move said movable frame when the treadle is operated, and means operating to yieldingly hold said 105 movable frame in raised condition.

2. In a machine of the character described, the combination of a stationary frame carrying a pressing-table, a movable frame, a presser-head carried by said movable frame 110 for coöperation with said pressing-table, a bell-crank pivoted at its angle to said stationary frame and pivoted at one arm thereof to said movable frame, a second bell-crank pivoted at its angle to the other, depending, arm of said first-named bell-crank, a link pivoted to the depending arm of said second bell-crank and to said movable frame, a treadle pivoted on the stationary frame, means connecting said treadle with the other arm of said second bell crank, and means 115 operating to yieldingly hold said movable frame in raised condition.

3. In a machine of the character described, the combination of a stationary frame carrying a pressing-table, a movable frame, a presser-head carried by said movable frame for coöoperating with said pressing-table, a 125

bell-crank pivoted at its angle to said stationary frame and pivoted at one arm thereof to said movable frame, a second bell-crank pivoted at its angle to the other, depending, arm of said first-named bell-crank, a link pivoted to the depending arm of said second bell-crank and to said movable frame, a treadle pivoted on the stationary frame, a link connected with said treadle and with

the other arm of said second bell-crank, and 10 means engaging with said link for yieldingly holding said movable frame in raised condition.

HENRY M. SVEBILIUS.

In the presence of—

W. B. DAVIES,
J. LANDERMAN.
